FOLDING PICK

Walter Johnson, Gary, Ind.

Application January 6, 1950, Serial No. 137,148

5 Claims. (Cl. 306—42)

1

This invention relates to a novel construction of folding or collapsible pick and more particularly to a pick having pivotally mounted prongs which are capable of being swung downwardly toward collapsed, inoperative position and so as to be disposed adjacent the pick handle when not in use.

More particularly, it is an aim of the present invention to provide a pick of relatively simple construction provided with means for detachably retaining the prongs of the pick head in extended, operative position yet which will permit the release of said prongs for downward swinging movement to an inoperative position when the pick is not in use.

Various other objects and advantages of the invention will hereinafter become more fully apparent from the following description of the drawing, illustrating a presently preferred embodiment thereof, and wherein:

Figure 1 is an exploded perspective view of the pick parts shown disassembled;

Figure 2 is a fragmentary side elevational view of the assembled pick;

Figure 3 is a fragmentary vertical sectional view taken substantially along a plane as indicated by the line 3—3 of Figure 4;

Figure 4 is a fragmentary sectional view taken at right angles to Figure 3 and substantially along a plane as indicated by the line 4—4 of Figure 2;

Figure 5 is a fragmentary top plan view of the pick, and

Figure 6 is a fragmentary sectional view, partly in side elevation of the pick head and showing the prongs thereof in a folded position.

Referring more specifically to the drawing, the novel folding pick in its entirety is designated generally 7 and includes an elongated tapered handle 8 which is oval shaped in cross section particularly adjacent its enlarged end and which is provided with a retaining band 9 of strap metal which is disposed around the enlarged end thereof, overlapped and secured thereto by suitable fastenings 10 which are anchored in the handle 8. A bolt 11 has one end anchored in the handle 8 and is disposed axially thereof and projects from the enlarged end of said handle and is provided with a diametrically extending bore 12 in its exposed portion.

The pick 7 also includes a head, designated generally 13, including a centrally disposed supporting member 14 of substantially the same shape in cross section as the enlarged end of the handle 8 and which has a threaded bore 15

extending axially therethrough for threadedly engaging the bolt 11. The head section 14 is provided at its lower end with oppositely disposed corresponding notches 16 which open outwardly of its side wall and of its bottom surface and which are formed in the widest part of said head section. The head 13 also includes a pair of corresponding longitudinally tapered prongs 17 which are provided, adjacent their enlarged ends, each with a transversely extending opening 18. Said enlarged ends of the prongs 17 are adapted to fit loosely in the notches 16 and the head section 14 is provided with openings 19 which transversely intersect the notches 16 and 15 which register with the openings 18 for receiving pins 20 for pivotally connecting the prongs 17 to the supporting head section 14. Each of the prongs 17 is provided with a projection 21 which depends from the underside thereof and adjacent its enlarged end.

A prong supporting member, designated generally 22 includes a disk 23 of oval shape to correspond in size and shape with the enlarged end of the handle 8 and which has a central opening 25 for receiving the bolt 11. The disk 23 is provided with aligned arms 25 which project from the remote portions of the periphery thereof and each of which is provided with an opening 26. The prong supporting member 22 is mounted directly on the enlarged end of the handle 8 and a washer 27 is mounted on the bolt 11 and supported on the disk 23. The supporting head section 14 is then screwed onto the bolt 11 and with the prongs 17 spread, as illustrated in Figures 2 and 3 and the projections 21 of said prongs are engaged in the openings 26 of the prong supporting member 22 before the head section 14 is completely tightened on the bolt 11 and so that said supporting or retaining member 22 will revolve with the head 13 as it approaches its fully applied position of Figures 2 and 3. It will thus be readily apparent that the retaining member 22 will maintain the prongs 17 in their extended positions of Figures 2 and 3 when the extensions 21 thereof are in engagement with the openings 26 since said prongs will rest on the outer ends of the arms 25 and the extensions 21 by engagement with the openings 26 will prevent any rotary movement of the retaining member 22 relatively to the head 13.

To prevent the head 13 from turning relatively to the bolt 11, the head section 14 is provided with a diametrical opening or bore 28 which registers with the opening 12 for receiving a retaining pin 29 which extends through the bores

12 and 28, as best seen in Figure 4 and which may be provided with a removable retaining element 30 on its shank end to prevent the retaining pin 29 from being accidentally dislodged.

From the foregoing it will be readily apparent that the pick when assembled, as previously described and as illustrated in Figures 2 and 3, may be utilized in a conventional manner and the pick prongs 17 will be positively held immovable relatively to the supporting head section 14 and the handle 8. When the pick is not in use it may be readily folded either by completely removing the head 13 from the bolt 11 and swinging the prongs 17 downwardly to a folded, substantially parallel position relatively 10 to the supporting head section 14, as illustrated in Figure 6, or after removing the retaining pin 29, the supporting head section 14 may be partially unscrewed from the bolt 11 sufficiently so that the prong retaining member 22 can be 15 disengaged from the extensions 21 and the head section 14 may then be positioned so that its widest part, from which the prongs 17 project, may be disposed transversely to the widest part 20 of the enlarged end of the handle 8 and with 25 the supporting arms 25 out of engagement with the prongs 17, said prongs may then be swung downwardly relatively to the head section 14 in folded positions substantially against the handle 8 and longitudinally thereof.

Various modifications and changes are contemplated and may obviously be resorted to, without departing from the spirit or scope of the invention as hereinafter defined by the appended claims.

I claim as my invention:

1. The combination with an elongated pick handle and a pair of pick prongs, of a bolt anchored in and projecting from one end of said handle, a supporting section combined with the supporting section having a threaded bore detachably engaging said bolt, said prongs having inner ends pivotally connected to the supporting section and projecting therefrom in opposite directions to one another, extensions secured to and depending from the prongs adjacent their pivoted ends, and a retaining member mounted on said bolt between the supporting section and handle and including supporting arms engaged under portions of said prongs for supporting the prongs in extended positions relatively to one another, said supporting arms being provided with apertures receiving the prong extensions and non-rotatably connecting the prong retaining member and pick head.

2. A structure as in claim 1, said supporting section having notches opening outwardly of one end thereof and opening outwardly of the head in opposite directions, the ends of the prongs 60 pivotally connected therein, said notches defining walls facing said end of the supporting sec-

tion and engaging the prongs for limiting the swinging movement thereof relatively to the supporting section and toward extended positions.

3. A structure as in claim 1, said handle being tapered throughout its length and the pick head being mounted on the enlarged end thereof, said handle and the supporting section being oval shaped in cross section, and said pick head being adapted to be backed off from the handle for disengaging the retaining member from the prongs whereby the prong supporting portions of the supporting section may be disposed transversely of the widest part of the enlarged end of the handle and transversely of the supporting arms of the retaining member for folding the prongs downwardly and against the handle.

4. In a folding pick, the combination with an elongated pick handle, of a pick head including a large nut and a pair of pick prongs, said nut having recesses opening outwardly of its periphery and outwardly of a lower end thereof defining downwardly facing wall surfaces, said prongs having inner ends disposed in said recesses and pivotally connected to said nut and mounted for swinging movement from extended, substantially aligned positions with portions of the prongs abutting the downwardly facing wall surfaces, only in one direction toward folded or collapsed positions, a bolt anchored in one end of the pick handle and extending therefrom and engaged with the nut to detachably mount the pick head on the handle, and a retaining member detachably mounted on said bolt between the handle and pick head and provided with elongated prong supporting members engaged under said prongs outwardly of their pivots for cooperation with said downwardly facing wall surfaces to retain the prongs in extended positions.

5. A folding pick as in claim 4, and means on said prongs having interfitting engagement in the prong retaining member non-rotatably connecting said retaining member to the pick head when said nut is engaged with the bolt and advanced to a position adjacent the handle.

WALTER JOHNSON.
